UNITED STATES PATENT OFFICE

WILBER L. LONG, OF KIRKSVILLE, MISSOURI, ASSIGNOR OF ONE-FIFTH TO H. B. YOUNG, ONE-FOURTH TO A. J. WHITE, AND ONE-TENTH TO DR. F. B. FARRINGTON, ALL OF KIRKSVILLE, MISSOURI

ELECTRIC SOCKET

Application filed August 12, 1930. Serial No. 474,804.

This invention relates to electric sockets and has relation more particularly to a device of this kind especially designed and adapted for use in connection with light 5 bulbs, fuse plugs and the like, and it is an object of the invention to provide a socket of this character constructed in a manner whereby the member for connection therewith may be applied quickly and without the 10 necessity of a screwing operation.

Another object of the invention is to provide a socket of this kind comprising means whereby a lamp globe or the like having a conventional thread sleeve may be applied 15 to the socket by a slip motion, thus avoiding the necessity of screwing the globe or the like into place.

Furthermore, it is an object of the invention to provide a socket of this kind where- 20 in a light globe or the like may be readily pushed into contacting position within the socket or readily pulled out as may be desired.

An additional object of the invention is to 25 provide a socket of this kind embodying a switch for readily controlling the flow of electrical energy.

The invention consists in the details of 30 construction and in the combination and ar- 35 rangement of the several parts of my im- proved electric socket whereby certain im- portant advantages are attained and the de- vice rendered simpler, less expensive and otherwise more convenient and advantageous 40 for use, as will be hereinafter more fully set forth.

The novel features of my invention will 45 hereinafter be definitely claimed.

In order that my invention may be the bet- 50 ter understood, I will now proceed to de- 55 scribe the same with reference to the accom- 60 panying drawings, wherein:—

Figure 1 is a view in section of a socket 55 constructed in accordance with an embodi- 65 ment of my invention, an applied globe being 70 shown in fragment and in elevation;

Figure 2 is a fragmentary detail sectional 75 view taken through the head member of the 80 socket, certain of the associated parts being 85 shown in elevation;

Figure 3 is a view in perspective of one of the grip members unapplied;

Figure 4 is a view in top plan of the socket 55 as herein disclosed with the hood and elec- trical conductors removed, one of the con- 60 tacts being indicated by broken lines and a second position of the switch blade being 65 also indicated by broken lines;

Figure 5 is a view in bottom plan of the 70 socket as illustrated in Figure 1 with the 60 lamp globe omitted;

Figure 6 is a view partly in section and 75 partly in elevation illustrating a socket con- 80 structed in accordance with a further em- bodiment of my invention;

Figure 7 is a view partly in plan and 85 partly in section of one of the contact mem- bers illustrated in Figure 6.

As disclosed in the accompanying draw- 70 ings, 1 denotes a head member in the form 75 of an inverted dish and which is produced 80 from suitable material non-conductive of 85 electricity. The flange 2 defining the mar- ginal portion of this head member 1 is tele- 90 scopically received within an end portion of 95 a sleeve 3 which may be of any desired ma- terial and of any preferred length.

Underlying the inner face of the head 80 member 1, and herein disclosed as disposed 85 radially thereof, is a contact plate 4 provided 90 at one end portion with a laterally directed 95 post 5 preferably at right angles thereto and which is snugly disposed through an open- 100 ing 6 provided in the head member 1 at a point in relatively close proximity to its 105 margin. Threaded upon the portion of the 110 post 5 outwardly of the head member 1 are the burrs 7 and 8, the burr 7 providing means 115 whereby the contact plate 4 is effectively held 120 in desired position with respect to the head 125 member 1.

Engaged in a conventional way between 130 the burrs 7 and 8 is a terminal of an electrical 135 conductor 9. At points equidistantly spaced 140 circumferentially thereof the head member 1 is 145 provided with the recesses or notches 10, herein disclosed as three in number, and in 150 each of which is received an end portion of a 155 resilient arm or strip 12. This end portion 160 of the arm or strip 12 is riveted, as at 14, or 165

otherwise securely anchored to the head member 1. Normally the arms or strips 12 have their free portions, or those portions thereof within the sleeve 3, arranged in convergence with said free portions provided with arcuate cross bars 15. The bars 15 which are curved longitudinally and which are secured between their ends to the arms 12, extend transversely of the arms and have their concave sides arranged innermost to adapt them to effectively engage a threaded ferrule or sleeve 16 or the like of a lamp globe, fuse plug, etc. This sleeve or ferrule may be readily slipped within the socket and effectively held therein by coaction of the cross members 15 of the arms 12 with the thread of the sleeve or ferrule 16 and whereby the contact 17 carried by the lamp globe or the like is maintained in desired electrical connection with the contact plate 4.

One of the arms or strips 12 has its connected extremity continued to provide a clip 18 overlying the outer face of the head member 1 and with which is adapted to be brought into effective electrical connection with an elongated switch blade 19. One end portion of this blade 19 is pivotally connected to an upstanding post 20 disposed through the head member 1 and with which is electrically connected through the medium of the burrs 21 the terminal of a second electrical conductor 23. The blade 19 is of a length to extend beyond the periphery of the head member 1 and said projected or extended portion carries a serrated or kindred head or finger piece 23 whereby the blade 19 may be readily shifted into either open or closed position with respect to the clip 18.

A hood 24 of metal or other desired material is engaged with the sleeve 3 and disposed over the head member 1, it being understood that this hood is entirely provided in a wall thereof with an opening through which the outer end portion of the blade 19 is directed and which opening will permit the desired movement of the blade 19 into either open or closed position.

In the embodiment of my invention as illustrated in Figures 6 and 7, the head member 1a has underlying its inner face and disposed radially thereof a spring contact plate 4a for engagement with the central contact 17a of the lamp. One end portion of this contact plate 4a is provided with a substantially perpendicularly directed post 5a extending through the head member 1a and with which is electrically connected through the medium of the nuts 6a and 7a the terminal of a conductor 9a. It is believed to be obvious that the nuts 6a and 7a are threaded upon the post 5a.

At a point substantially diametrically opposed to the binding post 5a is a second post 25 extending through the head member 1a and held thereto by the nuts 26 mounted on

the post 25 and engaging opposite faces of the member 1a. The outer or upper end portion of the post 25 has engaged therewith a second nut 27 coacting with the adjacent nut 26 for effectively holding the terminal of the conductor 22a in electrical connection with the post 25.

The post 25 extends a considerable distance inwardly or downwardly with respect to the head member 1a and terminates in an enlargement or head 28. This portion of the post 25 is angular in cross section and is freely and snugly engaged through the central portion of a contact plate 29 substantially crescent shape in plan. This plate 29 contacts with the outer shell 30 of the lamp and is maintained in such contact through the instrumentality of a coil spring 31 encircling the post 25 between the applied plate 29 and the adjacent nut 26.

The head member 1a carries a plurality of arms 12a each terminating in a cross bar 15a for engagement with the shell or sleeve 30 of the lamp whereby the socket and lamp are effectively maintained in desired assembled relation.

From the foregoing description it is thought to be obvious that an electric socket constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. An electric socket including a head, resilient arms secured at certain of their ends to the head and extending in convergent relation and in common direction from the head, and longitudinally curved bars secured between their ends to the other or free ends of the arms, the bars extending transversely of the arms and having concave sides facing each other.

2. An electric socket including a head of insulating material, a contact positioned at one side of the head, a binding post carried by the head and extending beyond said side thereof in spaced relation to the contact, a contact plate mounted upon the binding post for movement thereon toward and away from said side of the head, and a spring mounted on the post between the head and contact plate and normally urging the latter away from the head.

3. An electric socket including a head of insulating material, a contact positioned at one side of the head, a binding post carried

by the head and extending beyond said side thereof in spaced relation to the contact, a contact plate mounted upon the binding post for movement thereon toward and away
5 from said side of the head, a spring mounted on the post between the head and contact plate and normally urging the latter away from the head, resilient arms secured at certain of their ends to the head and extending in con-
10 vergent relation beyond said side of the head, and longitudinally curved bars se-
cured between their ends to the other or free ends of the arms, the bars extending trans-
versely of the arms and having their con-
15 cave faces facing each other.

In testimony whereof I hereunto affix my
signature.

WILBER L. LONG.
